FOLDING BOX

Henry G. Schmidt, Modesto, Calif.

Application October 5, 1935, Serial No. 43,676

2 Claims. (Cl. 229—34)

This invention relates to folding boxes; particularly representing improvements and simplifications over the box shown in my Patent No. 1,936,608, dated November 28, 1933, making it easier to manufacture and assemble the box, and providing for increased strength against collapse or distortion without any increase in the weight or manufacturing costs of the box.

These objects I accomplish by means of such structure and relative arrangement of parts as will fully appear by a perusal of the following specification and claims.

In the drawings similar characters of reference indicate corresponding parts in the several views:

Figure 1 is a plan of one form of box blank as stamped and ready for erection.

Figure 2 is a perspective of the box folded but with one end flap raised.

Figure 3 is a similar fragmentary view of the box partly erected.

Figure 4 is a perspective view of the completely erected box ready for use.

Figures 5 to 8 are fragmentary longitudinal sections of a box adjacent one end, showing various modified forms of box-side construction and means to lock the end flap against displacement.

Referring now more particularly to the characters of reference on the drawings, and particularly at present to Figures 1 to 4, the box is formed from a one-piece blank B of relatively stiff but bendable material of suitable character, having the necessary fiber strength combined with a certain springy flexibility and including a bottom 1, side walls 2, and end walls 3. The edges of the bottom are scored as at 4, the scoring enabling the blank to be manipulated so that the sides and ends may be bent to a vertical position from an initially flat or horizontal position.

Projecting from the end edges of the sides 2 are wings W whose length corresponds to the height of the box (which is that of the side and end walls) and in ordinary sized boxes is substantially half the width of the box. The lower edges E of the wings extend as direct continuations of the lines of scoring 4. The wings are divided into what may be considered two equal sections 5 and 6 by extra wide scoring 7 extending diagonally of the box from the corners of the bottom. When the sides and ends of the box are vertically disposed and the wings are bent at right angles to the sides along the line of scoring 8 provided therebetween, the edges E lie

adjacent and parallel to the bottom of the box and the inner edges of the wing sections 6 are adjacent each other.

The adjacent lower or inner sections 6 of the wings are then secured to the end walls by suitable adhesive A applied either to the inner faces of said sections, as shown in Figure 1, or to the inner face of the end walls 3, as indicated in Figure 3. The wing sections are secured to the end walls in the proper position at the time of manufacture and just before the folding operations, the remaining upper or outer sections 5 of the wings being unadhered. The wide scoring 7 (about $\frac{3}{8}$ inch) facilitates unfolding of the wing sections through the necessary 90° when erecting the box and gives great ease of operation, since the sections then bend readily about said scoring as a hinge.

The wing sections 5 are cut so that their upper edges extend as straight continuations of the upper edges of the side walls 2, while the outer edges of the sections 6 are cut so as to curve about a center taken at the junction of the edges E with the scoring 8.

The sides and ends of the box are therefore permanently tied together and the ends are braced and strengthened by the double thickness of material thus provided. At the same time the parts of the box may be folded or laid out flat as shown in Figure 2 without any strain or distortion such as would weaken the box and impair its rigidity and appearance when erected for use. Additional strength is imparted to the upper unadhered sections 5 of the wings by curved ribs 9 struck therein, which are concave relative to the inside of the box. These ribs insure movement of the wing portions to an upright position without possible buckling.

Flaps 10 substantially the same height as the sides 2 project outwardly from and extend along the outer edges of said sides from end to end, scoring 11 being provided in the material along the line of junction of said flaps with the sides. Shallow vertical inwardly projecting ribs 12 are formed in the flaps adjacent their ends to not only strengthen the flaps, but also to aid in maintaining the end flaps of the box locked, as will be seen later.

Formed with and projecting outwardly from the end walls 3 are flaps 13 the same height as but slightly less in width than said end walls; the blank being scored as at 14 between the flaps and end walls to provide for a relative bending movement therebetween. Relatively narrow

flaps 15 are formed along the outer edges of the flaps 13 to rest on the bottom of the box when said flaps 13 are in place, scoring 16 being provided in the blank along the line of junction of 5 said flaps. Shallow inwardly projecting ribs 17 are formed along the flaps 15 to stiffen the same. Projecting from the side edges of the flaps 13 and 15 are serrations in the form of sharp teeth 18, the bottom of the tooth spaces being substantially on a line with the side edges of the end walls 3.

When the box is sold to the user the end walls lie in longitudinal alignment with the bottom and the flaps 13 and 15 may either lie flat in out- 15 stretched relation or folded over onto the adjacent portions of the folded sides, as shown in Figure 2.

When it is desired to use the box the sides are opened up and the ends automatically move or fold toward each other so that the sides and 20 ends move to a vertical cooperating position together. The flaps 13 are then folded down inside the box, the serrations or teeth 18 being automatically deflected or bent from a straight-out 25 position as they engage the sides and move past the ribs 12 with the downward pressure on the flaps. These serrations or teeth forming a number of small individual and easily bent projections, it is unnecessary to score the flaps along 30 the bottom of the teeth in order for them to bend properly, and they thus maintain themselves in snug frictional engagement with the side walls of the box.

The flaps 13 of course enclose the wings and hold the latter rigidly in position and prevent 35 any unfolding or separating movement between the side and end walls. The upper edges of the wing sections 5 extending straight across the box at the top, are closely engaged by the folded over flaps 13 and prevent a possible collapse of the 40 latter along the top where they are weakened by the wide scoring 14. The engagement of the teeth 18 with the side walls holds the flaps rigidly in a vertical position without the use of adhesive; the endmost ribs 12 preventing any advancing 45 movement of the teeth from the position which they occupy when the flaps 13 are disposed in close relation with the wings.

When the flaps 10 are folded inwardly and are rigidly adhered to the side walls a double-ply 50 portion of material is provided in the sides of the box. This narrows or decreases the interior width of the box by the thicknesses of the extra plies, so that the flaps 13 as folded into the box and which from point to point of the teeth 18 55 across the flaps are somewhat wider than said narrowed interior width, become firmly engaged in the box and are prevented from unfolding. In order to insure against upward movement of the flaps 15 from position, the bottom edges of the 60 flaps 10 may be cut out from their ends as at 21 for a height and length equal to the end area of the flaps 15, so that the latter will be received in the shallow sockets or grooves thus formed, and will be firmly held against displacement independently of the teeth. The parts of the box 65 are thus firmly held in place without the necessity of the user employing adhesive of any character and the box is placed in condition for use in but a few seconds of time.

To stiffen the end walls 3 so that they will not bulge inwardly of the box, shallow vertical ribs 70 19 are struck in the same adjacent its ends, said ribs projecting outwardly of the box. Similar ribs 20 may also be formed in the flaps 13 to 75 project inwardly of the box.

In the form of box shown in Figure 5 the general construction is the same. The vertical edges of the side flaps 10a are spaced from the folded wings W sufficiently to leave grooves or panels 22 to receive the side edges of the flaps 13a, which 5 are devoid of teeth. An inwardly projecting shallow rib 23 is preferably formed down each such edge of the flaps 10a, so as to increase the depth of the groove 22. The bottom flap receiving sockets 21a are also retained.

In Figure 6 the tooth edged flap construction is retained but the side flaps 10b are provided at the bottom and adjacent their ends with notches 24 to receive the ends of upstruck and relatively large ribs 25 formed on the bottom 15 flaps 15b, there being one such rib on each flap. In this manner an even more secure locking of the flaps in place is obtained.

In the construction of Figure 7 the toothed flaps are retained but the side walls of the box 20 are of a single thickness, the side flaps 10 or their equivalent being omitted. To then strengthen the relatively thin sides against collapse, they are therefore longitudinally ribbed adjacent the top, as at 26, a number of vertically spaced ribs 25 being preferably provided; while vertical end-flap engaging ribs 12a are also provided.

In Figure 8 the sides of the box are strengthened by relatively short inturned flaps 27 bent inwardly of the sides along the top and secured thereto. In this instance the end-flap retaining ribs are shown as replaced by vertical rows of inwardly projecting circular protrusions 28.

In all cases the various score lines are designed as to width in proportion to the thickness of the 35 box material used and with regard to the degree of bending required, so as to provide for the necessary folding and unfolding operations without tearing or destroying the fibers of the material, while avoiding an undue springiness along the 40 lines of bending. For instance, the scores 11 must be wider than the scores 4 because the flaps 10 must fold through 180° while the sides or ends only bend through a 90° arc. Similarly, the scores 14 must be even wider than the scores 11 (or 41 may be double), since the flaps 13 must bend through 180° over a double thickness of material—the ends 3 and wings W.

From the foregoing description it will be readily seen that I have produced such a device as 50 substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I 60 claim as new and useful and desire to secure by Letters Patent is:

1. A folding box formed from a one-piece bendable blank cut to form bottom, side and end walls, means integral with the blank and connecting the adjacent side and end walls in a manner 6 to enable said walls to be disposed in vertical cooperating relation with each other or to lie in flat folded relation to the bottom wall, flaps formed with the end wall as extensions along the top edges thereof and adapted to be folded over into 7 the box after the side and end walls have been vertically disposed and enclosing the connecting means thereof to prevent folding movement of the walls, and relatively deep serrations formed along the edges of the flaps; the distance across 7

the flaps between the outer edges of the serrations being initially greater than the interior width of the box whereby when said flaps are folded into the box, the serrations will bend to extend substantially lengthwise of and frictionally engage the side walls of the box.

2. A structure as in claim 1, in which the box

is formed with inwardly projecting protrusions down the sides thereof adjacent their ends and beyond which the serrations pass when the flaps are in folded position whereby to form stops for engagement with the bent serrations to prevent possible unfolding of the flaps. 5

HENRY G. SCHMIDT.
